Primary Examiner — Anhdao Doan*Assistant Examiner* — Mary Malley(74) Attorney, Agent, or Firm — Alston & Bird LLP(57) CLAIM

The ornamental design for a carry case, as shown and described.

DESCRIPTION

FIG. 1 is a perspective view of a carry case according to our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dash-dash-break broken lines visible in FIGS. 1-7 are representative of stitching of the carry case for illustrative purposes only and form no part of the claimed design. The strap of the carry case is shown with a symbolic break in its length. The appearance of any portion of the article between the break lines forms no part of the claimed design.
